UNITED STATES PATENT OFFICE.

WILLIAM KEMP, OF ST. LOUIS, MISSOURI.

GAS ANALYZER.

Application filed September 15, 1928. Serial No. 306,260.

My invention relates to a gas analyzer and particularly to an analyzer operating on the absorption principle to determine the amount of an absorbable gas in a mixture containing such gas and another or others inert to the absorption material. My apparatus is especially adapted to indicate the percentage of carbon dioxide contained in flue gases of furnaces.

One object of my invention is to improve the mechanical construction of such an apparatus so that it will be light, strong and durable. Another object of my invention is to provide improved means for supplying a uniform flow of gas to the diffusion plate of the device.

In the accompanying drawings, which illustrate one form of analyzer made in accordance with my invention, Figure 1 is a vertical, longitudinal section; Figure 2 is a top plan view of the absorption chamber; and Figure 3 is a section taken on the line 3—3 of Figure 1.

My apparatus comprises an absorption chamber including means for holding a diffusion plate in position, an injector for supplying a uniform flow of flue gas to the diffusion plate, and an indicating or recording device communicating with the absorption chamber.

The absorption chamber consists of a rectangular steel tank 5 containing the absorption material 6, preferably caustic potash solution. In the top of the tank 5 is a square opening 7 surrounded by a flange 8 which may be made integral with the tank but which, for convenience in manufacture, is preferably made separate and welded in position. On the flange 8 is a cover 9 held in place by screws 10. Projecting inwardly from the flange 8 is a ledge 11 on which is supported the diffusion plate 12 of porous material, such as asbestos board. The plate is secured in place by a clamping frame 13 held by screws 14 in the cover. Leading from the cover is a pipe 15 connected to the injector. The use of the clamping frame and screws provides a simple and effective means for securing a gas tight joint between the flange and the diffusion plate.

The body of the injector consists of an upright pipe 16 terminating in a T fitting 17, the branch 18 of which leads to the smoke stack or other source of flue gas. A plug 19 closes the upper end of the fitting and carries a nozzle 20. In the interior of the upper end of the pipe 16 is a plug 21 carrying a small pipe 22 extending down through the pipe 16 to a point past the entrance of the pipe 15. On the lower end of the pipe 16 is a T fitting 23 closed by a plug 24 and connected by a horizontal pipe 25 with a similar T fitting 26. The upper end of the fitting 26 is closed by a flange 27 having a vent 28, and the lower end by a plug 29 in which is secured the overflow pipe 30. This pipe projects above the horizontal pipe 25 a predetermined distance and thus determines the amount of pressure under which the flue gas is delivered to the diffusion chamber, from which it escapes through opening 33 in one of its walls.

The space above the absorption fluid communicates through a pipe 31 with any suitable indicating or recording device 32. It will be understood that the flue gas, before being discharged into the diffusion chamber, is passed through one or more dehydrating cells to remove all moisture and also through a filter to remove the free carbon and other solid matter. These devices are not shown as they form no part of the present invention.

The operation of my invention is as follows: A jet of water is discharged through the nozzle 20 into the pipe 22 carrying with it the flue gases from the pipe 18. Water of condensation collects in the lower end of the pipe 16 passing through pipe 25 into the connection 26 where it forms a water seal. The height of the water in the seal depending upon the distance of the top of the pipe 30 above the horizontal pipe 25 determines the pressure at which the gases are delivered through the pipe 15 to the diffusion chamber. This pressure will be constant notwithstanding variations in the pressure of the water delivered by the nozzle and consequently a uniform flow of gas will be delivered to the diffusion chamber. Any excess of flue gas above

that which can be delivered through pipe 15 at the determined pressure will be carried over into the trap with the water and escape through vent 28. The diffusion chamber is thus supplied with a constant and uniform flow of flue gases which diffuse through the plate 12 into the absorption chamber where the carbon dioxide (CO_2) is absorbed by the liquid 6. As is well known, under this condition the pressure of the gases in the chamber 5 will vary in proportion to the amount of carbon dioxide in the gas and the variation of pressure is communicated through pipe 31 to any suitable instrument 32 where it is either indicated or recorded as desired.

Having fully described my invention, what I claim as new and desire to secure by Letters Patent of the United States is:

1. In a device of the class described, the combination with an absorption chamber provided with an opening in the top, a flange surrounding said opening, a diffusion plate supported on said flange, a cap for said flange, and means carried by said cap for clamping the diffusion plate against the flange.
2. In a device of the class described, the combination with an absorption chamber provided with an opening in the top, a flange surrounding said opening, a diffusion plate supported on said flange, a cap for said flange, a clamping frame in said cap and bearing on said plate, and screws in said cap bearing on said frame.
3. In a device of the class described, the combination with an absorption chamber provided with a porous plate, of a diffusion chamber enclosing said plate, an injector for supplying gases to said diffusion chamber, and a liquid seal for determining the pressure at which said gases are supplied.
4. In a device of the class described, the combination with an absorption chamber provided with a porous plate, of a diffusion chamber enclosing said plate, an injector for supplying gases to said diffusion chamber, and a liquid seal communicating with said injector and determining the pressure therein, said seal being provided with a vent for surplus gases.

50 In testimony whereof, I hereunto affix my signature, this 13th day of September, 1928.

WILLIAM KEMP.
